CABINET FOR DISPENSING PAPER TOWELS, WAXED PAPER, AND ALUMINUM FOIL

Harry Preble, Jr., Cross River, N. Y., assignor to National Can Corporation, Chicago, Ill., a corporation of Delaware

Application March 3, 1955, Serial No. 34,845

Term of patent 14 years

(Cl. D4—3)

Fig. 1 is a perspective front and left hand side view of a cabinet for dispensing paper towels, waxed paper and aluminum foil showing my new design;

Fig. 2 is an enlarged rear view thereof; and

Fig. 3 is a fragmentary perspective front and side view of the cabinet showing at least the upper two covers partially open.

I claim:

The ornamental design for a cabinet for dispensing paper towels, waxed paper and aluminum foil, substantially as shown and described.
